United States Patent Office

Des. 190,836
Patented July 4, 1961

190,836

BOTTLE OR THE LIKE

Theodore T. Roselaar, 85 East End Ave.,
New York, N.Y.

Filed Aug. 19, 1959, Ser. No. 57,230

Term of patent 3½ years

(Cl. D58—9)

FIG. 1

FIG. 4

FIG. 2

FIG. 4 is a sectional view taken substantially along line 4—4 of FIG. 1.

The back of the bottle is substantially identical with the front. The bottom and top are plain and unornamented.

I claim:

The ornamental design for a bottle or the like, as shown and described.
